Inventor.

United States Patent Office.

CHARLES R. ABBOT, OF ELMIRA, NEW YORK.

Letters Patent No. 65,150, dated May 28, 1867.

IMPROVEMENT IN PROPS FOR CARRIAGE TOPS.

The Schedule referred to in these Letters Patent and making part of the same.

TO ALL WHOM IT MAY CONCERN:

Be it known that I, CHARLES R. ABBOT, of Elmira, in the county of Chemung, and in the State of New York, have invented certain new and useful improvements in "Props for Carriage Tops;" and I do hereby declare that the following is a full, clear, and exact description thereof, reference being had to the accompanying drawings, forming a part of this specification.

Figure 1 is a perspective view, and

Figure 2 a vertical section of the mode in which I prefer to make my improved "prop."

Figures 3 and 4 are similar views of a variation in my mode of forming the "prop."

My invention consists in making the shank of the carriage-top "prop" in two pieces lapping past each other, the lower part being very short, so as to allow the leather to be put over it without wrinkling, as will hereinafter appear.

A represents the plate, which is fastened by screws to the frame of the top. B is the lower half of the shank, projecting outwardly from plate A, to which it is cast or riveted. The length of this part B is just a little greater than its diameter, and it is bevelled off, as shown in fig. 2. B' is the upper part of the shank, having a knob, *a*, formed on its outer end, and being of a sufficient length to serve as the bearing for the ribs of the top. Its lower end is bevelled off so as to make a lap-joint with the lower part B. C is the finishing-ferrule, which encloses part B and a portion of part B', and which rests upon and presses down the leather *c*. D is a screw, passing through the ferrule C and the two parts B and B' where they meet, thus fastening those three pieces together as firmly as one.

In the ordinary prop, with the shank in one long piece, it is impossible for the trimmer to neatly and smoothly fit the leather, because the leather has to be considerably stretched in order to pass it over the prop. In my invention the lower half of the prop is so short, and bevelled on one side, that the leather can be put over it without any perceptible stretching, thus enabling the workman to make a neater job. The knob, too, being fast to the shank, cannot turn and unscrew. This mode of forming the prop is better and cheaper than any known to me.

Figs. 3 and 4 show the shank in two parts, B and B', and with the ferrule C, but without the screw D.

There are several notches and tongues, *o*, formed on the lap surfaces of the parts B and B', so as to prevent the upper part from pulling away from the lower part. *v v* are two small studs on the plate, passing up through the leather, and taking in corresponding holes in the bottom of the ferrule C to prevent its turning. The knob *i* of this prop is screwed upon the shank.

The operation is the same as in the other prop, shown in figs. 1 and 2, so far as putting on the leather is concerned. After the leather is fitted the part B' is applied to part B. The ferrule is then slipped over; the ribs are then put on, and the knob *i* screwed on.

There are various modes in which the two-part shank may be made. I have described the two best known to me.

What I claim as my invention, and desire to secure by Letters Patent, is—

1. The shank B B', when made in two parts, and constructed and operating substantially as and for the purposes set forth.

2. The shank B B', in combination with plate A, ferrule C, and screw D, substantially as and for the purposes set forth.

3. Securing the shank B B' and ferrule C together by means of tongue and groove *o* and pins and holes *v*, substantially as and for the purposes set forth.

In testimony that I claim the above-described invention I have hereunto signed my name this 20th day of February, 1867.

CHARLES R. ABBOT.
